UNITED STATES PATENT OFFICE.

ALBERT A. BRUDER AND AUGUST J. BRUDER, OF DETROIT, MICHIGAN.

VENTILATING DEVICE FOR WATER-CLOSETS.

962,499.

Specification of Letters Patent. Patented June 28, 1910.

Application filed February 4, 1910. Serial No. 542,076.

To all whom it may concern:

Be it known that we, ALBERT A. BRUDER and AUGUST J. BRUDER, citizens of the United States of America, residing at Detroit, in the county of Wayne and State of Michigan, have invented certain new and useful Improvements in Ventilating Devices for Water-Closets, of which the following is a specification, reference being had therein to the accompanying drawings.

This invention relates to a ventilating attachment for closets.

The invention consists of the matters hereinafter set forth, and more particularly pointed out in the appended claims.

Referring to the drawings, Figure 1 is a plan view partly broken away of a closet equipped with an attachment embodying features of the invention; Fig. 2 is a view partly in side elevation and partly in section of the closet and attachment; Fig. 3 is an enlarged view in detail of one form of the attachment and adjacent portion of the seat; Fig. 4 is a plan view partly broken away of a modified form of the ventilator; Fig. 5 is a view in cross section of the ventilator showing the adjacent portions of the closet in dotted lines; Fig. 6 is a view in section, enlarged of a modified form of the device; and Fig. 7 is a view in section of another modification.

In the drawings, a closet 1 of conventional type has a seat 2 hinged in the usual manner to a shelf 3 to the rear of which is the usual ventilating pipe 4 adapted to be connected to a ventilating flue as in standard closet constructions. A hollow casing 5 preferably of metal is secured detachably to the under side of the shelf above the rim of the rear portion or "kidney" of the closet as it is termed. This casing has a transverse passage indicated at 6 to open through a pipe 7 into the same ventilating flue with which the pipe 4 is connected or a like ventilating passage. A hollow casing 8 that conforms in outline to the rim 9 of the closet is interposed between the latter and the underside of the seat 2. In the preferred form indicated in Fig. 3 the casing is of metal with flanges 10 secured by screws 11 or like means to the seat. A sheet metal plate 12 forms the inner wall of the casing adjacent the seat. A gasket 13 of rubber or like material adapted to rest upon the seat frame is secured to the lower face of the frame 8 by

suitable means, as for example, a metal channel bar 14 whose flanges are slightly convergent to retain the gasket. An opening 15 is formed through the rear portion of the casing to register with the passage 6 when the seat is in normal position and an aperture 16 in the inner wall of the casing at the front of the seat is likewise connected by a duct 17 formed by the walls of the casing with the passage 6.

Instead of being secured to the seat and shelf the ventilator may rest directly on the rim of the bowl as indicated in Figs. 4, 5 and 6 in which construction it is preferably formed of a single piece of porcelain or cast metal 18 having its under side 19 conforming in cross section to the upper face of the bowl rim 9 with the rear ventilating duct 20 and a forward ventilating duct 21. Cement or like material is placed between the meeting faces of the bowl and ventilator and it is further held in place by a depending forward lug 22 adapted to hook around the bowl rim and screws 23, bolts or like fastening means passing through the back of the ventilator and engaging the body of the bowl. As a further modification, the ventilator may be cast integrally with the bowl as indicated in Fig. 7 with front aperture 24 and rear opening 25 connected through a duct 26 with the ventilating shaft of the closet.

The ventilator is readily attached to closets of standard construction and furnishes complete system of ventilation, air entering through the top of the bowl to the seat opening and passing out through the ventilator. The latter does not materially alter the external proportions or design of the closet and may be attached without disturbing the plumbing connections.

Obviously, changes in details of construction may be made without departing from the spirit of the invention, and we do not limit ourselves to any particular form or arrangement of parts.

What we claim as our invention is:—

1. A ventilating attachment for closets comprising a hollow casing interposed between the closet seat and shelf and the closet rim, and provided with a pair of ventilating passages, one of which has an inlet opening in the inner wall of the casing near the front of the closet, and the other of which has an inlet opening in the inner wall

of the casing near the rear of the closet, the outlets of both passages being adjacent each other at the rear of the closet.

2. A ventilating attachment for closets comprising a hollow casing detachably secured between the closet seat and shelf and the closet rim, and provided with a pair of vent passages, one of which has an inlet opening in the inner wall of the casing near the front of the closet, and the other of which has an inlet opening in the inner wall of the casing near the rear of the closet, the outlets of both passages being adjacent each other at the rear of the closet.
- 15 3. A ventilating attachment for closets comprising a hollow casing interposed between the closet seat and shelf and the closet rim, and provided with a pair of ventilating passages, one of which has an inlet opening in the inner wall of the casing near the front of the closet, and the other of which has an inlet opening in the inner wall of the casing near the rear of the closet, the outlets of both passages being adjacent each other at the rear of the closet.
- 20 4. A ventilating attachment for closets comprising a hollow casing detachably secured between the closet seat and shelf and the closet rim, and provided with a pair of vent passages, one of which has an inlet opening in the inner wall of the casing near the front of the closet, and the other of which has an inlet opening in the inner wall of the casing near the rear of the closet, the outlets of both passages being adjacent each other at the rear of the closet.
- 25 5. A ventilating attachment for closets comprising a hollow casing interposed between the closet seat and shelf and the closet rim, and provided with a pair of ventilating passages, one of which has an inlet opening in the inner wall of the casing near the front of the closet, and the other of which has an inlet opening in the inner wall of the casing near the rear of the closet, the outlets of both passages being adjacent each other at the rear of the closet.

seat and the closet seat shelf into two sections, each conforming to the contiguous portion of the closet.

4. A ventilating attachment for closets comprising a hollow casing detachably secured between the closet seat and shelf and the closet rim, and provided with a pair of vent passages, one of which has an inlet opening in the inner wall of the casing near the front of the closet, and the other of which has an inlet opening in the inner wall of the casing near the rear of the closet, the outlets of both passages being adjacent each other at the rear of the closet.
- 30 5. A ventilating attachment for closets comprising a hollow casing detachably secured between the closet seat and shelf and the closet rim, and provided with a pair of vent passages, one of which has an inlet opening in the inner wall of the casing near the front of the closet, and the other of which has an inlet opening in the inner wall of the casing near the rear of the closet, the outlets of both passages being adjacent each other at the rear of the closet.
- 35 6. A ventilating attachment for closets comprising a hollow casing detachably secured between the closet seat and shelf and the closet rim, and provided with a pair of vent passages, one of which has an inlet opening in the inner wall of the casing near the front of the closet, and the other of which has an inlet opening in the inner wall of the casing near the rear of the closet, the outlets of both passages being adjacent each other at the rear of the closet.
- 40 7. A ventilating attachment for closets comprising a hollow casing detachably secured between the closet seat and shelf and the closet rim, and provided with a pair of vent passages, one of which has an inlet opening in the inner wall of the casing near the front of the closet, and the other of which has an inlet opening in the inner wall of the casing near the rear of the closet, the outlets of both passages being adjacent each other at the rear of the closet.

In testimony whereof we affix our signatures in presence of two witnesses.

ALBERT A. BRUDER.
AUGUST J. BRUDER.
